UNITED STATES PATENT OFFICE.

CECELIA I. SULLIVAN, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

WOVEN CARRIER.

1,338,797.

Specification of Letters Patent.

Patented May 4, 1920.

Application filed July 9, 1917. Serial No. 179,348.

To all whom it may concern:

Be it known that I, CECELIA I. SULLIVAN, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The present invention, like that of U. S. Patent No. 1,211,275, granted under date of January 2, 1917, has relation to pocketed carriers made of woven material, for instance carriers on the order of those which 15 are used for holding and carrying cartridges, packaged first-aid supplies, etc. As in the case of the invention of the said patent, the present invention relates more particularly to the covers or flaps which are 20 provided in connection with the pockets of carriers of the said general class. It is an improvement upon the box or boxed or hood-like covers or flaps which are shown and described in such patent, and which are 25 characterized by having deep side-wings or skirts which together with the associated front form a depending body or flange that extends around the upper portion of a pocket in such manner as to completely in- 30 close such portion without openings at the opposite sides of the closed and covered pocket.

The invention consists in an improved boxed cover or flap embodying novel features of construction by which a double top for weather protection is produced, the process of manufacture is simplified and expedited, and the manufacturing cost is reduced.

40 An embodiment of the features of the invention is shown in the drawings, in which latter,—

Figure 1 is a front elevation of a portion of a woven carrier having a cover or flap 45 containing the said features.

Fig. 2 is a view thereof looking from the left-hand side in Fig. 1.

Fig. 3 is a top view of the cover or flap shown separately.

50 Fig. 4 is a view in vertical section on line 4, 4, of Fig. 3.

The drawings show the invention applied in connection with one of the pockets 1, and a portion of the supporting-band 2,

of a woven carrier of known construction in 55 general.

The cover shown in the drawings comprises two pieces of woven material, both preferably narrow webs woven with regular selvages. One of these pieces forms the top 60 3, and the other forms the depending body or flange 4. The use of narrow strips cut from a larger web is contemplated as a modification, and when these are employed their raw or cut side margins will be turned 65 over and stitched or otherwise fastened in place so as to give firm smooth edges. The use of selvaged narrow webs is preferred, inasmuch as in the case of such use the seams at the junction of the top 3 and the depending body or flange 4 are less bulky and clumsy.

The top 3 is of suitable dimensions to cover the open top of the pocket and is prolonged rearwardly to form the rearward attaching extension 5 by which the cover or flap is connected with the supporting-band 2. Preferably, the said extension is entered into a housing-slit provided in the upper portion of the supporting-band, 70 75 as shown in Fig. 2, and the cover or flap is made fast to the supporting-band by approved fastening means, in this case consisting of stitches 6 passing through the side-walls 7, 7, of the housing-slit and the 80 85 interposed attaching extension 5.

The depending body or flange 4, which encloses the opposite lateral sides and the front of the pocket, is attached by its upper margin to the front end and side margins of the 90 top 3, preferably by means of stitches 8, 9. The two ends of the strip of which the body or flange 4 is made are hemmed as at 4^a, 4^b, Figs. 2 and 3, to conceal and protect the 95 raw or cut edges thereof.

The double top comprises two thicknesses of the strip of material of which the top is composed. This strip primarily is somewhat more than twice as long as the distance from the supporting-band to the front of 100 the pocket. In the double top the said strip is folded back upon itself, making thereby a double thickness for a little greater length than the distance just mentioned. The raw or cut extremity of its shorter under portion is hidden and protected by being turned in between the said shorter portion and the main portion, and is secured in place by 105

fastenings 10, Fig. 4, preferably stitches which pass through all three thicknesses of the material. At the sides of the double top the margins of both thicknesses of the latter are fastened to the upper margin of the body or flange 4 by means of the stitches 8, which pass from the outside of the body through all three thicknesses of material to the upper side of the top. This mode of application of the side fastenings produces a tendency of the side-portions of the depending body or flange to occupy an inward position close to the sides of the pocket, and reduces the tendency of the said side-portions to bow outward laterally. At the front of the double top, the forward fold of the latter is fastened to the upper margin of the depending body or flange 4 by the stitches 9. Preferably, the said forward fold is turned downward on the order of a short flange, and the said stitches pass from front to rear through the two thicknesses of the fold and also through the said upper margin of the body or flange 4. This gives a smoother front angle, without any tendency of the front margin of the top to turn upward like a lip. Preferably, also, the said forward fold of the top is located at the back of the adjoining portion of the upper margin of the depending body or flange, and thereby is hidden and protected by the latter.

In practice, the front corners of the cover or flaps are given a rectangular shape in horizontal cross-section by a pressing or ironing operation.

The cover or flap shown in the drawings and described above is simple in construction, contains a minimum quantity of material, is produced without waste, and admits of being manufactured conveniently and quickly.

Fastening means for securing the cap or cover in closed condition will be provided in practice, usually. The drawings show fastener devices 11, 12 of so-called glove-fastener type.

I claim as my invention:—

1. A pocketed carrier having a boxed 50 pocket-cover or flap which is connected

flexibly at the back thereof to the carrier, and which comprises a top formed of one piece of woven material that is doubled back upon itself so as to produce a double thickness for weather protection, and a depending body or flange formed of a second piece of woven material which is fastened by its upper margin to the side margins and front fold of the double top. 55

2. A pocketed carrier having a boxed 60 pocket-cover or flap which is connected flexibly at the back thereof to the carrier, and which comprises a top formed of one piece of woven material that is doubled back upon itself so as to produce a double 65 thickness for weather protection, and a depending body or flange formed of a second piece of woven material which is fastened by its upper margin to the side margins and downturned front fold of the double top. 70

3. A pocketed carrier having a boxed 75 pocket-cover or flap which is connected flexibly at the back thereof to the carrier, and which comprises a top formed of one piece of woven material that is doubled 80 back upon itself so as to produce a double thickness for weather protection, the said top having a rearward attaching extension, and a depending body or flange formed of a second piece of woven material which is fastened by its upper margin to the side margins and front fold of the double top. 85

4. A pocketed carrier having a boxed 90 pocket-cover or flap which is connected flexibly at the back thereof to the carrier, 85 and which comprises a top formed of one piece of woven material that is doubled back upon itself so as to produce a double thickness for weather protection, the said top having a rearward attaching extension, 90 and a depending body or flange formed of a second piece of woven material which is fastened by its upper margin to the side margins and front end of the top.

In testimony whereof I affix my signature 95 in presence of two witnesses.

CECELIA I. SULLIVAN.
